DESIGN FOR A TOY

Herman S. Hyde, Deerfield, Mass.

Application July 9, 1936, Serial No. 63,744

Term of patent 7 years

To all whom it may concern:

Be it known that I, Herman S. Hyde, a citizen of the United States, residing in Deerfield, county of Franklin, State of Massachusetts, have invented a new, original, and ornamental Design for a Toy, of which the following is a specification, reference being made to the accompanying drawing, forming a part thereof;

Fig. 1 of the drawing is a side elevational view of a toy showing my design and Fig. 2 is a plan view thereof.

I claim:

The ornamental design for a toy as shown.

Signed this 6th day of July, 1936.

HERMAN S. HYDE.
